SWINGING CLOSURE LOCKING DEVICE

Roy E. Fowler, Watkinsville, Ga., assignor of one-half to Gladys H. Johnston, Watkinsville, Ga.

Application July 28, 1945, Serial No. 607,514

4 Claims. (Cl. 292—144)

1

The invention relates to a swinging closure locking device, and more especially to an automobile door lock.

A primary object of the invention is the provision of a device of this character whereby a swinging door can be automatically locked in such manner as to be relatively free of rattle, the device being hydraulically controlled and so dimensioned as not to occupy any greater space in its fitting than any ordinary door lock or the like.

Another object of the invention is the provision of a device of this character precluding the loosening of the door in fastened position as might be occasioned by worn parts of the device, as the hydraulic action thereof compensates for such wear.

A further object of the invention is the provision of a device of this character which is simple in construction, reliable and efficient in operation, strong, durable, self locking, readily and conveniently applied in place, adaptable to any swinging door, and inexpensive to manufacture and install.

With these and other objects in view, the invention consists in the features of construction, and combination and arrangement of parts as will be hereinafter more fully described, illustrated in the accompanying drawings, and pointed out in the claims hereunto appended.

In the accompanying drawing:

Figure 1 is a horizontal sectional view taken substantially along the line 1—1 of Figure 3 through a locking device constructed in accordance with the invention.

Figure 2 is a top view thereof.

Figure 3 is a fragmentary elevation of a motor vehicle body and its door, certain parts thereof being broken away showing the device applied thereto and in locking position.

Similar reference characters indicate corresponding parts throughout the several views in the drawing.

Referring to the drawing in detail, the locking device constituting the present invention, comprises an elongated circular body 10, having in opposite ends, fore and aft piston chambers 11 and 12, respectively, the former having fitted therein a floating piston 13, which is fitted with a packing cup 14 at its inner end. The chamber 12 has a reciprocating piston 15 which is also fitted with a packing cup 16.

The outer end of the piston 13 is formed with a reduced area 17 over which is telescoped a socketed latching head 18, its socket 19 being of a corresponding size to the area 17 for slidably

2

interfitting therewith. Between the head 18 and the area 17 is a coiled compression spring 20 which urges the head outwardly. This head 18 is adapted to be accommodated within the crotch 21 of a rocking keeper 22, pivoted at 22' to a door jamb 23 for a swinging door 24, as best seen in Figure 3 of the drawing. This interfitting of the head 18 and keeper provides for anti-rattling when the door 24 is locked by the device.

Extending longitudinally within the body 10 is a fluid passageway or duct 25 for communication of the chambers 11 and 12 with each other, so that oil, which is the preferred hydraulic fluid, within one chamber can pass under pressure to the other of said chambers in the throwing of the head 18 to locked position.

Externally built on the piston 15 is a spring cage 26 in which works a plunger 27, having pivotal connection at 28 with a throw rod or lever 29, which is pivoted at 30 (see Figure 3) to a supporting plate 31 mounted on the door 24 beneath the body 10 at the proper location. The throw rod or lever 29 has connected thereto, by a pivot 32, a suitably guided striker member 33 for engaging the jamb 23 when the door is closed, thus actuating the rod or lever, against the resistance of a coiled expansion spring 34 housed within the cage 26.

Surrounding the piston 15 is a coiled expansion spring 35 which has contact with a shoulder 36 on the said piston 15 and against the body 10.

Formed within the body 10 is a by-pass duct or passage 37 which is a return lead from the chamber 11 to the chamber 12, and in the elbow 38 in this passage is a ball return check valve seat 39, for a ball valve 39', which is held normally to its seat by a tensioned hand release stem 40, which is hand accessible for the working thereof. The passage 37 communicates with an air bleeding valve 41 carried by the body 10. When it is desired to release the locking device, the stem is manually lifted so the pressure within the chamber 11 will be relieved and the fluid may pass into passage 37 which forms a reservoir. This allows the piston 13 to move back under the action of spring 20 and relieves pressure so that keeper 22 may swing and allow the door to open. When the door is opened, rod 33 is released and pressure is released from springs 34 and 35 so that piston 15 is retracted. This results in drawing the fluid back into the chamber 12. When the door is closed, member 33 actuates lever 29 so as to move piston 15 for forcing the fluid through passage 25 into chamber 11 and exerting pressure on piston 13 so as to compress spring

20 and exert force against head 18 so that the keeper 22 is held in locking position to prevent opening of the door.

The spring 20 compensates for any wear on the head 18 or the keeper 22, and functions as an anti-rattling medium, while the hydraulic functioning of the locking device also prevents the door becoming loose because of worn parts as the hydraulic pressure constantly biases the device towards locked position. The piston 15 is a pumping piston, while the piston 13 is a pressure piston in the working of the locking device.

The spring 34 within the case 26 is a shock-spring, while the spring 35 acts to return the piston 15 back to normalcy for the unlocking operation of the device, as should be apparent.

A disk type check valve 42 caged in a suitable recess communicates with the piston accommodation cylinder and with the intake end of the passage 37. Its purpose is to check any backflow of liquid that would otherwise collect in the passage 37 when the piston 15 moves outwardly or forwardly.

A careful consideration of the foregoing description in conjunction with the invention as illustrated in the drawings will enable the reader to obtain a clear understanding and impression of the features of merit and novelty sufficient to clarify the construction of the invention as hereinafter claimed.

Minor changes in shape, size, materials and rearrangement of parts may be resorted to in actual practice so long as no departure is made from the invention as claimed.

What is claimed is:

1. A locking device for fitting in a keeper on a swinging door, comprising a body having spaced piston chambers in communication with each other, a pressure piston within one chamber, a pumping piston in the other chamber, a spring tensioned locking head on the pressure piston, striker means for operating the pumping piston for the working of the pressure piston to locking position under fluid pressure from one chamber to the other thereof, a hand operated stem for relieving pressure on the pressure piston for the releasing of the head from the keeper, a by-pass duct connecting with both piston chambers and a spring-tensioned valve normally closing said conduit.

2. A locking device for fitting in a keeper on a swinging door, comprising a body having spaced piston chambers in communication with each

other, a pressure piston within one chamber, a pumping piston in the other chamber, a spring tensioned locking head on the pressure piston, striker means for operating the pumping piston for the working of the pressure piston to locking position under fluid pressure from one chamber to the other thereof, and means hand operated for relieving pressure on the pressure piston for the releasing of the head from the keeper.

3. A locking device for fitting in a keeper on a swinging door, comprising a body having spaced piston chambers in communication with each other, a pressure piston within one chamber, a pumping piston in the other chamber, a spring tensioned locking head on the pressure piston, striker means for operating the pumping piston for the working of the pressure piston to locking position under fluid pressure from one chamber to the other thereof, and means hand operated for relieving pressure on the pressure piston for the releasing of the head from the keeper including shock absorbing means between the pumping piston and striker means.

4. A locking device for fitting in a keeper on a swinging door, comprising a body having spaced piston chambers in communication with each other, a pressure piston within one chamber, a pumping piston in the other chamber, a spring tensioned locking head on the pressure piston, striker means for operating the pumping piston for the working of the pressure piston to locking position under fluid pressure from one chamber to the other thereof, and means hand operated for relieving pressure on the pressure piston for the releasing of the head from the keeper including shock absorbing means between the pumping piston and striker means including means for returning the pumping piston to normalcy when relieved by the striker means to free the head from the keeper.
